UNITED STATES PATENT OFFICE.

GEORGE WOOD CLAPP AND ERVIN S. ULSAVER, OF NEW ROCHELLE, NEW YORK.
DEVICE FOR USE IN CONNECTION WITH THE ARTICULATION OF ARTIFICIAL TEETH.

1,079,540.

Specification of Letters Patent. Patented Nov. 25, 1913.

Application filed April 4, 1913. Serial No. 758,745.

To all whom it may concern:

Be it known that we, GEORGE W. CLAPP and ERVIN S. ULSAVER, citizens of the United States, and residents of New Rochelle, county of Westchester, and State of New York, have invented an Improvement in Devices for Use in Connection with the Articulation of Artificial Teeth, of which the following is a specification.

10 The object of our invention is to provide artificial plates to be used in the act of making dentures as a guide in setting up the artificial teeth upon the plate which fits the gums, such artificial plates acting as a floor 15 or support in the articulator to insure the proper level or position of the occlusal or grinding edges or surfaces of the teeth when being positioned on the rubber plate.

The common assumption is, that the teeth 20 of the upper and lower sets may be made to relatively work in an up and down movement of the jaw, but this is not natural and is not, in the true sense, effective in masticating food to fit it for digestion. To enable 25 the teeth of one jaw to function properly with the teeth of the other jaw, it is necessary to have contacting portions of the teeth so set that a side or grinding motion may be had by the jaw, without the teeth interlocking to prevent such movement, or becoming so separated during the side movement that their grinding efficiency is reduced or lost. It is difficult to set the teeth to insure this proper functioning in mastication, 30 and it is to facilitate such arranging of the teeth on the rubber plates which fit the gums, that our improved artificial plate is intended. The upper surface of said plate being 35 so shaped as to correspond to the positions 40 which the cusps of the upper teeth should occupy, when both upper and lower teeth are to be made, the lower teeth may then be placed in right relations to the upper teeth, and both sets will then effectively 45 operate in grinding food.

Our invention consists of a plate, preferably of U-shaped construction, adapted to be used in an articulator when making dentures, said plate having exposed curved surfaces which conform to the curvatures found most desirable to insure the best grinding action of the teeth when set up complete in the rubber plate for use in the mouth. Our artificial plate is formed with predetermined 55 curved surfaces by tests upon separate skulls,

from which curves are prepared and the law of averages determined.

Our invention will be better understood by reference to the drawings, in which:

Figure 1 is a perspective view illustrating our improved artificial plate separated from the articulator; Fig. 2 is a plan view of the same; Fig. 3 is a front edge view; and Fig. 4 is a side edge view of the same; and Fig. 5 is a side elevation of the articulator with our improved artificial plate in position as used in setting up the artificial teeth.

5 and 6 are the two parts of the usual articulator which is employed in setting up dentures. Around the base portion 5 is built up the foundation 4 and around the upper part 6, is built the foundation 7, the compositions of these foundations being usually of plaster of Paris and wax. As shown in Fig. 5, the articulator is being employed in the act of making a denture, in which the teeth 9 for the rubber plate 8 of the upper jaw are being set up; and in which operation, our improved artificial plate 2 is arranged in position which would correspond to the occlusal or grinding surfaces of the upper teeth of the jaw, the upper surfaces of said plate having special curvatures to be later described. The said artificial plate may also be provided with projecting teeth or prongs 3 by which it may be fastened on the wax or other foundation.

The artificial plate 2 is preferably of ductile metal and of U-shape in plan, as shown in Figs. 1 and 2, and has its operative surface formed with curvatures which are more fully disclosed in Figs. 3 and 4.

Re particularly describing the characteristic curvatures of the operative surface of the artificial plate, with reference to what is shown, namely, the plate corresponding to the lower teeth, the extreme front portion 11 is made with inclined surfaces 12, extending forward and downward, 100 said inclination being, with respect to the general plane of the plate. Furthermore, the rear arms 10 of the plate are curved laterally inward and downward and at the intermediate portions 13, there is, in effect, a reverse curve, the same being the blending of the two ends of 12 into the forward ends of the side portions 10, of the plate. The inclined portion 12 allows the upper central teeth to extend 110

down slightly below the level of the laterals and bicuspids in setting up the denture, and the lower portions 13, at the reverse curves, permit the bicuspids and the first molars 5 to come slightly lower than the second molar teeth, whereby the various teeth are given approximately such positions for their grinding edges or surfaces, that when the lower teeth have been placed in proper relations to the upper teeth whose positions 10 are determined by the curves of this plate and the natural lateral motion is given to the jaw in chewing, the upper teeth will function with the lower teeth in the most 15 effective manner to enable the grinding operation to take place between all the bicuspids and molars on one side and without interlocking of the incisors or front teeth.

20 Where the artificial plates are to be employed in the setting up of dentures for both the upper and lower sets of teeth, to be used together, there would be no restriction in providing proper curves to the surfaces of the plates; and in these cases, the most scientific manner of arranging the curves is resorted to, the same being by duplicating the curves found in the grinding or occlusal surfaces of the best specimens of 25 natural teeth. This information has been obtained by examining many skulls containing the best specimens of natural teeth, and the character of the curves so provided has been studied, and the law of averages 30 determined. The curves so determined and plotted are duplicated in the operating surfaces of our improved artificial plate, the curves in said portions of the plate being made to correspond to the average curves 35 derived from the curves taken from numerous examples of actual teeth, as thus above stated. It will be understood that the shape of the operative or exposed surfaces of the plate containing curved portions is most im- 40 portant, while the under surface is immaterial.

The forming of the plate of relatively thin metal is illustrated in the drawings, though we do not confine ourselves to any 45 particular shape for the under surfaces, nor to any particular manner of attaching the said plate to the built up form or foundation upon which it sets. That the purpose of providing this described curvature to the 50 artificial plate and then setting the teeth to correspond to the said curvature, may be readily understood, the following explanation is given: When the natural teeth of 55 both jaws are all present, and their position is perfect, portions of teeth of both sides of the jaw are in contact at the same time during the act of masticating or chewing; that is, if a morsel of food is between the back teeth of the right side, the lower 60 jaw is thrown to the right before it com-

55 incences the grinding motion, and it grinds the food by first coming up into contact with the upper teeth and then sliding back to the middle position. At the same time, the back teeth of the other side of the mouth, 60 provide what may be called "balancing contact" and fix the lower jaw in its proper position, with the least possible exercise of muscular force, and permit it to devote all 65 its muscular force upon the side on which grinding of the food is taking place. When 70 artificial teeth replace the natural teeth, it is desired to give the person the greatest 75 grinding power possible, as this greatly facilitates digestion of the food. This can 80 be done only by setting the grinding surfaces of the teeth to have the same inclinations that had been present in the natural 85 teeth. As this inclination varies with each tooth, there has been a great deal of difficulty in properly positioning artificial teeth in the rubber plate to insure their proper functioning, in use. The present methods in use involve a great deal of trouble and expenditure of time to determine the position 90 to be given to each of the artificial teeth, and frequently the setting is unsatisfactory because of the failure of correctness in such 95 positioning.

Our improved artificial plate is intended 100 to obviate these difficulties to the present methods of positioning teeth and the object of our plate is to serve two main purposes, namely: The outer boundary, when the plate is looked upon from above, determines the outline to which the teeth should be set so that the outer edges of the teeth in each case just come to the edge of the plate. The different curves in the plate 105 surface represent the different inclinations of the grinding surfaces of the teeth to secure the very best results by the patient. If the upper teeth are set so that all occlusal or grinding parts of the teeth touch the plate, the teeth will be in proper position 110 to give the patient the very best possible service. In practice, artificial plates of this character will be provided in various sizes for the dentist and from which he may select as occasion may require, to fit jaws of 115 different sizes. In those cases where the teeth remaining in the patient's head are of such character as to prevent the use of the plate unchanged, the plate may be modified or shaped by bending or filing as may be 120 necessary to overcome any particular specific difficulty which may arise. Moreover, it is evident, that while our improved artificial plate is more accurate in defining the 125 best arrangements of artificial teeth in new plates, where both upper and lower sets are to be made for the same patient, a single plate, namely, that of the lower jaw as shown in the drawing, would suffice for both sets, because if the upper set were made 130

to conform to this plate, the lower set may be subsequently made to function properly with the upper set previously built, and in this way a single artificial plate 5 of our invention may be sufficient in preparing both sets of teeth. If, however, only an upper set of teeth is required, then the artificial plate corresponding to the grinding or occlusal surfaces of the teeth of the 10 lower jaw should be provided for use on the articulator; and likewise, when the lower teeth are to be made then an articulator plate of our invention may be provided to correspond to the grinding or occlusal 15 surfaces of the teeth of the upper jaw. In these latter cases, however, should the natural predetermined and most desirable curvatures found as herein stated, not properly conform to the remaining teeth in the patient's jaws, then the metal should be modified 20 as to its curved surfaces to enable a set of artificial teeth to be produced to properly function with these remaining in the patient's mouth, whatever the condition of 25 these teeth may be.

While we have shown our improved plate in **U** form and thin, because it is lighter and more easily bent when necessary in adapting it for use, it will be evident that this particular removal of the metal in the middle part is a matter of immateriality when considering the invention in its broadest sense, and while we prefer the construction of the 30 plate shown, we do not restrict ourselves to 35 the minor details thereof, as these may be modified without departing from the spirit of the invention.

In this application we do not claim the "method" of setting up dentures in an articulator, as that will form subject matter 40 of a separate application, a division of this application.

Having now described our invention, what we claim as new and desire to secure by Letters Patent, is:

1. An artificial plate for use in setting up

dentures, having a body providing an operative surface upon which the teeth of the denture are to be set up and by which they are positioned vertically and in inclination, said surface made with curvatures forming undulations lying in vertical planes and also providing inclined surfaces to horizontal planes, which are inverse or complementary to the curvatures and inclinations 55 to be given to the occlusal or grinding surfaces and edges of the teeth of the completed denture or set of teeth thus being set up.

2. An artificial plate for use in setting up dentures, having a body provided with 60 an operative surface upon which the teeth of the denture to be made are to be set up and by which they are positioned vertically, said surface made with curvatures taken from the average curves derived from curves 65 of the occlusal or grinding surfaces of a plurality of different jaws.

3. An artificial plate for use in setting up dentures, consisting of a plate of hard material and said plate shaped to present 70 curved portions disposed over its surface to correspond to the points or cusps of the occlusal or grinding surfaces of the artificial set of teeth to be produced as the result of setting up the denture upon the said plate. 75

4. An artificial plate for use in setting up dentures, consisting of a plate of hard material and said plate shaped to present curved portions disposed over its surface to correspond to the points or cusps of the occlusal 80 or grinding surfaces of the artificial set of teeth to be produced as the result of setting up the denture upon the said plate, combined with an articulator having a foundation upon which the artificial plate is attached. 85

In testimony of which invention, we hereunto set our hands.
